JOSEPH D. GALLAGHER, OF GLEN RIDGE, NEW JERSEY, AND HARRY JONES, OF SUFFERN, NEW YORK, ASSIGNEES TO AMERICAN BRAKE SHOE & FOUNDRY COMPANY, OF MAHWAH, NEW JERSEY, A CORPORATION OF NEW JERSEY.

BRAKE-SHOE.

1,159,010.

Specification of Letters Patent.

Patented Nov. 2, 1915.

Application filed May 4, 1915. Serial No. 25,688.

To all whom it may concern:

Be it known that we, JOSEPH D. GALLAGHER, a citizen of the United States, and a resident at Glen Ridge, county of Essex, and 5 State of New Jersey, and HARRY JONES, a citizen of the United States, and a resident of Suffern, in the county of Rockland and State of New York, have made and invented 10 certain new and useful Improvements in Brake-Shoes, of which the following is a specification.

This invention relates to brake shoes, and more particularly to that class or type which are formed with hard and soft metal sections which are separately cast, so that the metal of each section may possess the exact and desired characteristics.

The object of the present invention is to provide the separately cast sections with interlocking ends which are drawn into rigid engagement by the contraction of the sections as they cool, whereby the usual reinforcing member of expanded metal or wire mesh may be dispensed with.

25 A further object is to provide a common support, taking the form of a reinforcing back, and upon which are separately cast hard and soft sections, the arrangement and configuration of such resulting in their 30 secure anchorage to the reinforcing back and the rigid attachment of one to the other.

Other objects and advantages will appear as the description proceeds, wherein it is to be understood that changes in the precise 35 embodiment of the invention can be made within the scope of what is claimed without departing from the spirit thereof.

The preferred embodiment of our invention is disclosed in the accompanying drawings, wherein:

Figure 1 is a plan view of the wearing face of a brake shoe embodying the characteristic features of our invention; Fig. 2 is a plan view of the back thereof; Fig. 3 is a 45 view in longitudinal section of the foregoing; Fig. 4 is a view in cross section taken on the line 4—4 of Fig. 2.

Referring specifically to the several views, the brake shoe which is therein disclosed is formed with a steel reinforcing back 6 of the usual and preferred form, and includes the integral attaching lug 7, whereby the shoe may be secured to the brake head.

Separately cast upon the ends of the rein-

forcing back 6, which acts as a common support, are the hard metal end sections 8, the molds in which the same are formed being of such configuration that the molten metal flows up, around, and embeds, the ends of the reinforcing back 6 therein. The resulting end stops 9 promote and insure the secure anchorage of the end sections to the reinforcing back. The hard metal end sections are provided with the dove-tailed or widening recesses 10, the side walls of which 55 converge toward the center of the shoe, and are accordingly adapted to interlock with dove-tailed projections 14, which are formed upon the central section 12. The central section 12 which is formed of soft metal is 60 cast between the confronting ends of the hard metal sections, and the shrinkage or contraction thereof causes a slight separation between the end walls 15 of the projections and the bottom walls 16 of the dove-tailed recesses 10. A slight separation also 65 occurs between the meeting ends of the hard and soft sections as at 17, so that the various sections may expand slightly in an independent manner, preventing the shoe 70 from straightening out as it becomes heated in service. The slight separations between the various sections also materially increases 75 the heat-radiating surface for the sections, affording ample opportunity for the dissipation 80 of frictional heat.

The shrinkage or contraction of the various sections results in the oblique walls 18 of the end projections being drawn into forced and wedged contact with the corresponding and oblique walls 11 of the dove-tailed recesses 10. In this manner, a secure 85 anchorage is had between the various sections, and the metal of the central sections, which flows up through the openings 13 in 90 the reinforcing back, in connection with the end stops 9, practically eliminates all danger or likelihood of a section, or portion thereof, becoming detached or separated 95 from the shoe.

What we claim is:—

1. A brake shoe comprising a common supporting member, hard metal sections anchored thereto and provided with recesses therein, and a soft metal section anchored 105 to said common supporting member and provided with projections extending within and interlocking with said recesses.

2. A brake shoe comprising a reinforcing back, separated hard and soft metal sections anchored thereto provided with interlocking ends.
5. 3. A brake shoe comprising a reinforcing back, hard metal sections anchored thereto and provided with confronting and widening recesses therein, and a soft metal section anchored to said back and separated from said hard metal sections, said soft metal sections provided with projections fitting within and interlocking with said recesses.
10. 4. A brake shoe comprising a reinforcing back, hard metal end sections anchored thereto, and provided with dove-tailed recesses therein, a soft metal central section anchored to said back and slightly separated from said end sections, and provided with dove-tailed projections fitting within and stepping short of the bottom walls of said recesses.
15. 5. A brake shoe comprising a reinforcing back, hard metal end sections anchored thereto and provided with dove-tailed recesses therein, a soft metal central section anchored to said back and slightly separated from said end sections, and provided with dove-tailed projections fitting within and
20. 30. stopping short of the bottom walls of said recesses, the oblique walls of said projections and recesses being drawn into forced

contact by the contraction of the central section.

6. A brake shoe comprising a common 35 supporting member, separated metal sections anchored thereto and provided with interlocking ends.

7. A brake shoe comprising a reinforcing back, separated sections of metal anchored 40 thereto and provided with interlocking ends.

8. A brake shoe comprising a reinforcing back, sections anchored thereto and provided with confronting and widening recesses therein, and a central section anchored to said back and separated from said end sections, said central sections provided with projections fitting within, and interlocking with, said end section recesses. 45
